IMPACT ABSORBING ARTICLE OF FOOTWEAR

Filed June 9, 1947

FIG. 1

FIG. 2

INVENTOR,
Clement T. Lee

BY

Bernard Bluest
ATTY.

UNITED STATES PATENT OFFICE

2,469,969

IMPACT ABSORBING ARTICLE OF
FOOTWEAR

Clement T. Lee, Cleveland, Ohio

Application June 9, 1947, Serial No. 753,459

8 Claims. (Cl. 36—7.8)

1

This invention relates to impact absorbing shoes, and especially to a removable overshoe particularly adapted to withstand relatively heavy impacts, such as received by a parachutist in striking the earth.

Heretofore there have been various types of rubber soles and cushioning members provided for shoes, such as would be worn by a parachutist or by a person working in the vicinity of vibrating machinery or by people who are especially sensitive to foot shocks when working on a steel or concrete floor for long periods of time. However, such special cushioning members provided for shoes have not been sturdy enough nor load absorptive enough to give desirable action when subjected to extremely heavy impacts, such as those occasioned when a parachutist strikes the earth.

The general object of this invention is to provide a new and improved article of footwear especially adapted for receiving and cushioning heavy impacts.

A further object of the invention is to provide an effective, removable cushion overshoe for a parachutist.

Another object of the invention is to provide an inexpensive, easily manufactured overshoe that has a removable impact absorbing member.

Another object of the invention is to provide an impact absorbing member having adjustable load supporting and shock absorbing characteristics.

The foregoing and other objects and advantages of the invention will be made apparent as this specification proceeds.

Reference now is made to the accompanying drawing wherein:

Fig. 1 is a perspective view of a parachutist boot having an overshoe embodying the principles of the invention engaged therewith; and

Fig. 2 is an enlarged vertical section through the overshoe of Fig. 1 with the boot indicated in broken lines as occupying the overshoe.

With particular reference to the details shown in the drawing, the invention is illustrated as incorporated in an overshoe, generally indicated at 10. It is adapted to be applied in the usual manner to a shoe or boot, such as the parachutist boot 11 shown. The overshoe 10 is made from any conventional material and it usually comprises either natural or synthetic rubber which is formed into the shape of a foot portion of a shoe to form an enclosing member 12. In some instances, this enclosing member may be reinforced with fabric, but in all events, it is desired that said enclosing member 12 be somewhat

2

elastic and normally slightly smaller than the foot portion of the shoe or boot with which it is to be engaged. Thus, the enclosing member of the overshoe 10 will be expanded slightly when engaged with the shoe of the person wearing the same and the natural properties of the enclosing member will retain it in tight engagement with the shoe of its wearer. The enclosing member 12 is shown as provided with a continuous downwardly directed rib portion or shoulder 13 on its inner surface and such shoulder 13 is adapted to engage with a load distributing member such as a plate 14 which is of solid construction so that a person wearing the overshoe 10 will be supported on the plate 14.

As a salient feature of the invention, a combined rubber pad and air cushioning device is provided below the plate 14 for receipt and absorption of load and shock applied to the overshoe 10 by its wearer, such as when the person wearing the overshoe would strike the earth after a parachute jump. The novel load supporting element of the invention comprises a rubber pad 15 which is positioned in the lower portion of the enclosing member 12 and may be sealed within an inflatable envelope 16 but does not completely fill the same. The envelope 16 may be made of rubber or rubberized fabric or other desired material and it is shown as removably positioned in the overshoe. A conventional inflation device, such as a valve 17, is incorporated in the envelope 16 so that the air pressure set up therein can be varied whereby the load supporting and shock absorbing characteristics of the combination of the rubber pad 15 and the envelope 16 can be adjusted to a desired value for the individual wearer of the overshoe 10. The rubber pad 15 is shown as of a closed cell construction wherein the individual cells 18 have gas pressure set up therein but this pressure does not vary appreciably with variations in the air pressure within the envelope 16. This "closed cell" rubber of which the pad 15 is made can be formed by any of a number of conventional methods but if it is desired to vary the pressure within the rubber pad 15, as well as the pressure in the envelope 16, then one should use another type of cellular rubber wherein the cells are intercommunicating with some of them opening exteriorly of the pad whereby the same pressure would be set up within the rubber pad as would exist within the envelope 16.

Fig. 2 also shows that a relatively thick sole 19 is provided on the enclosing member 12 and this sole, like the remainder of the enclosing member, may be formed of any conventional con-

struction, usually fairly resilient rubber so as to aid in cushioning or absorbing impact load on the wearer of the overshoe.

Preferably the valve 17 is so positioned that it extends upwardly through a hole 20 of the plate 14 into the space below the shank portion 21 of the boot 11 whereby the valve 17 is readily exposed for variation of the pressure within the envelope 16 but, yet it does not interfere in any manner with the engagement of the boot 11 with the overshoe 10. By means of a suitably shaped instrument, capable of convenient insertion between the side wall of the overshoe and the adjacent part of the boot or shoe of the wearer, the valve may be opened by depressing its stem to relieve the air pressure. This is desirable after a parachutist lands, before proceeding on foot.

While it has been stated that the shoulder 13 is continuous, it will be realized that this shoulder may be provided in the shape of spaced lugs formed, usually, integral with the enclosing member and possibly such spaced lugs could only be formed at, for example, four circumferentially spaced portions within the enclosing member. This would facilitate engagement of the plate 14 with the shoulders but would not change the load transmitting relationship of the construction shown.

While one complete embodiment of the invention has been illustrated and described herein in detail, it will be realized that modifications of this construction may be made without departing from the scope of the invention as defined in the appended claims.

Having thus described my invention, what I claim is:

1. An overshoe of the class described comprising an enclosing member made of an elastic material and adapted to be removably engaged with the foot portion of a shoe, said enclosing member being of such normal size as to be expanded when engaged with a shoe to compress against it tightly, said enclosing member having a downwardly directed shoulder formed on its interior spaced from the lower portion thereof, a plate member positioned in said enclosing member and engaged with said shoulder to be retained against upward movement thereby, a rubber pad positioned within said enclosing member below said plate member but not filling such space completely, an inflatable member positioned around said rubber pad, and means for inflating said inflatable member so that the pressure therein can be controlled to vary the load supporting and shock absorbing characteristics of the overshoe.

2. An overshoe of the class described comprising an enclosing member made of an elastic material and adapted to be removably engaged with the foot portion of a shoe, said enclosing member being of such normal size as to be expanded when engaged with a shoe, said enclosing member hav-

ing a downwardly directed shoulder formed thereon spaced from the lower portion thereof, a plate member positioned within said enclosing member and engaged with said shoulder to be retained against upward movement thereby, a rubber pad positioned within said enclosing member below said plate member, an inflatable member positioned around said rubber pad, and a valve for said inflatable member so that the air pressure therein can be controlled to vary the load supporting and shock absorbing characteristics of the overshoe.

3. An overshoe adapted to absorb impact load for the wearer, which overshoe comprises an elastic foot enclosing part adapted to retain itself in engagement with the foot of its wearer, an inflatable member received in said overshoe, a rubber pad enclosed in said member to provide a combined air and cushion load receiving device, and means for distributing load over the surface of said inflatable member and said rubber pad.

4. An overshoe as in claim 3 wherein a valve is provided for said inflatable member and it extends therefrom up through said load distributing means into the shank portion of an article of footwear that occupies the foot enclosing part of the overshoe.

5. An article of footwear adapted to absorb impact load for the wearer, said article comprising a foot enclosing part and a hollow sole that opens substantially throughout its entire area into the bottom of said foot enclosing part, a load supporting and shock absorbing cushion means occupying the hollow sole and adapted to be inserted into the same through said foot enclosing part, and a detached relatively stiff load distributing element disposed over said cushion means and constituting the bottom of the foot enclosing part.

6. An article of footwear according to claim 5, wherein the article is formed with integral parts for retaining said load distributing element against upward displacement.

7. An article of footwear according to claim 5, wherein said cushion means consists of an inflatable envelope and a resilient pad.

8. An article of footwear according to claim 7, wherein the resilient pad is permanently enclosed within said inflatable envelope.
